(57) **CLAIM**

The ornamental design for a drawer wire strike, as shown and described.

DESCRIPTION

FIG. 1 is a top perspective view of the drawer wire strike of the present invention showing our new design;

FIG. 2 is a bottom perspective view thereof;

FIG. 3 is a bottom plan view thereof;

FIG. 4 is a top plan view thereof;

FIG. 5 is a front elevational view thereof;

FIG. 6 is a side elevational view thereof; and,

FIG. 7 is a rear elevational view thereof.
